CLAIM

The ornamental design for a dog boot as shown and described.

DESCRIPTION

FIG. 1 is a perspective view of the dog boot;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 illustrates the dog boot on the foot of a dog.

The broken lines showing a dog in FIG. 8 depict environmental subject matter. The broken lines on the exterior surface of the dog boot depict stitching and the remaining broken lines depict portions of the dog boot. All broken lines form no part of the claimed design.

1 Claim, 8 Drawing Sheets
